UNITED STATES PATENT OFFICE.

ALEXANDER DURAND, OF LOS ANGELES, CALIFORNIA.

TAILOR'S IRON.

1,213,602.

Specification of Letters Patent. Patented Jan. 23, 1917.

Application filed May 23, 1916. Serial No. 99,456.

To all whom it may concern:

Be it known that I, ALEXANDER DURAND, a citizen of the United States, residing at Los Angeles, in the county of Los Angeles 5 and State of California, have invented a new and useful Tailor's Iron, of which the following is a specification.

My invention relates to tailors' irons. In the tailors' art irons are used for the purpose 10 of pressing clothing, these irons being used in combination with a certain amount of moisture which is ordinarily supplied to the clothing by sprinkling, or by the use of a wet cloth, this moisture being turned to 15 steam as the face of the iron is passed over the goods.

The principal object of my invention is to provide an iron which will generate its own steam as needed from a suitable source of 20 water supply.

A further object of my invention is to provide an iron in which the steam is generated by the heat of the iron, and in which the amount of steam supplied may be readily 25 controlled by the operator.

A still further object of my invention is to provide means in such an iron whereby the amount of steam can be controlled by twisting the handle of the iron so that it will not 30 be necessary to employ any special form of finger or thumb operated valve.

A further object of the invention is to provide in a water supply pipe regulating means to prevent the flooding of the iron. 35

In the accompanying drawing, I have illustrated, and in the following specification I describe, a gas heated iron, this heating feature forming no part of my invention which may be applied to an electric 40 iron, or one otherwise heated, if desired.

In the drawings which are for illustrative purposes only: Figure 1 is an end view of an iron embodying my invention as seen from the rear, a portion of the gas connection 45 being broken away to better illustrate the invention. Fig. 2 is a side view of the iron illustrated in Fig. 1, a portion of this iron being shown in section on a plane represented by the line x^2-x^2 of Fig. 1, viewed 50 in the direction of the arrow. Fig. 3 is a cross section on an enlarged scale of the valve means employed in my invention.

In the form of the invention illustrated 55 in the drawings, an iron is shown consisting of a body 11, a top 12, and a heating means 13. Formed in the toe of the iron on the face

thereof is a steam distributing channel 14, this channel being closed by a dove-tailed plate 15 having a plurality of small holes 16 therein. Connected to the steam distributing channel 14 by a small channel 17, is a steam well 18 in which a screen 19 is placed, the interior of this screen communicating through a small pipe 20 with the top of a steam chamber 21 which is formed in 60 the top of the iron 12. The steam chamber 21 is provided with a lower wall 22 having ribs 23 thereon, the wall 22 being directly over the heating element 13 which is preferably gas fired. The heating element 13 consists of a gas burner 24 which is provided with a mixer 25, this mixer being provided with air through openings 26 in an air supply pipe 27, and being provided with gas through a gas connection 28, the supply of 65 gas being controlled by a gas valve 29. A flexible hose, not shown, is secured to the gas connection 28 for the purpose of furnishing the necessary gas. Secured in the top of the iron is a front standard 30 and a rear standard 31. Passing through holes in 70 these standards is a handle shaft 32, this shaft being provided with a button head on the front end thereof, and being provided with a spacer 34 and a nut 35 on the other 75 end thereof. A bracket lever 36 is secured to a wooden handle 37 which surrounds the handle shaft 32 and is located between the standards 30 and 31, the bracket lever 36 being secured to the handle 37 by means of a 80 screw 38. The bracket lever 36 is bent as shown in Fig. 2, extending up inside the standard 31 and over the top of the standard 31, and downwardly outside the standard 31 between the spacer 34 and the nut 35. 85 Formed on the extreme lower end of the lever 36 is a small pin 39, this pin passing through a hole in a flat spring 40, this spring being secured to the top of the iron by means of a screw 41. Secured in the top of 90 the iron is a water supply pipe 42, this water supply pipe extending up and being connected to a water valve 43, this valve consisting of an outer body 44 in which a plug 45 revolves, the plug having a small opening 46 95 which may be turned so as to shut off the supply of water, or may be turned in the body 44 to pass any desired amount of water. A lever 47 is secured to the plug 45, this lever also passing through a hole in the flat 100 spring 40. Secured in the upper end of the valve 43 is a check valve 48, this valve hav-

ing a small ball restrained therein by means of a pin 50, the ball 49 being of the proper size to fit solidly against a valve seat 51. A water connection 52 is secured on the top of the check valve 48 and a small diaphragm 53 is secured between the connection 52 and the check valve 48, the diaphragm 53 having a small hole 54 therein for the purpose of regulating the amount of water passing 10 to the iron. A plug 55 is screwed in an opening in the top of the iron through which water may be removed and through which the pipe 20 may be cleaned.

The method of operation of the invention 15 is as follows: Under normal conditions the spring 40 holds the various parts in the position shown in full lines in Fig. 1, the valve 44 being closed in this position. Gas being supplied to the burner 13, the interior and 20 face of the iron is heated, and the wall 22 is maintained in a highly heated condition. Whenever it is desired to pass steam into the fabric to be heated the operator turns the handle 37, through the lever 36 and forcing 25 the flat spring 40 into the dotted position as shown in Fig. 1, thus turning the plug 45 so that water will be passed through the pipe 42 into the chamber 21. This water falls on the highly heated wall 22 and 30 is converted into steam, this steam passing downwardly through the pipe 20 into the well 18, and through the opening 17 and the channel 14 to the small opening 16 through which it is injected into the goods 35 being pressed, the diaphragm 53 preventing an excessive amount of water from flowing so that the iron will become flooded, and the supply of water is instantly shut off when the operator releases the handle 37. The 40 check valve 48 retains the steam in the iron so that it cannot flow back into the water supply pipe.

I claim as my invention:—

1. In a tailor's iron; a heating element;

walls forming a steam generating chamber 45 above said heating element; a water pipe connected into the top of said steam generating chamber; a valve in said water pipe, standards secured to the top of said iron; a handle rotatably mounted in said standards; 50 a bracket lever rigidly secured to one end of said handle inside the rear standard, said bracket lever being bent over to project down outside said standard; spring means for holding said handle normally in the 55 closed position; and means by which said bracket lever actuates said valve.

2. In a tailor's iron; a heating element; walls forming a steam generating chamber 60 above said heating element; a water pipe connected into the top of said steam generating chamber; a valve in said water pipe, standards secured to the top of said iron; a handle rotatably mounted in said standards; 65 a bracket lever rigidly secured to one end of said handle inside the rear standard, said bracket lever being bent over to project down outside said standard; and a flat leaf spring secured to the top of said steam chamber and so connected to said bracket 70 lever and said valve as to hold them normally in the closed position.

3. In a tailor's iron; a heating element; walls forming a steam generating chamber 75 above said heating element; a water pipe connected into the top of said steam generating chamber; a valve in said water pipe, standards secured to the top of said iron; a handle rotatably mounted in said standards; 80 a bracket lever rigidly secured to said handle; spring means for holding said handle normally in the closed position; and means by which said bracket lever actuates said valve.

In testimony whereof, I have hereunto set 85 my hand at Los Angeles, California, this 17th day of May, 1916.

ALEXANDER DURAND.
